United States Patent Office

Des. 220,815
Patented May 25, 1971

220,815

TYPEWRITER

William B. Sklaroff, Narberth, Pa., assignor to Litton
Business Systems, Inc., New York, N.Y.

Filed May 4, 1970, Ser. No. 22,789

Term of patent 14 years

Int. Cl. D18—02

U.S. Cl. D64—11

Fig. 2

FIG. 1 is a front perspective view of a typewriter showing my new design; and

FIG. 2 is a rear perspective view thereof.

Some of the keys have been omitted from the keyboard in FIG. 1 for convenience of illustration.

I claim:

The ornamental design for a typewriter, as shown and described.
